UNITED STATES PATENT OFFICE.

JOHN J. DALY, OF NEWTON, MASSACHUSETTS.

BOX-TOE SHOE.

Application filed October 23, 1923. Serial No. 669,948.

This invention relates to the manufacture of box toe shoes, and particularly to the method of uniting the usual thermo-plastic box toe blank to the toe tip and insole. Heretofore, the accepted practice has been to temporarily anchor the box toe, when softened, to the toe tip and insole by driving a pair of anchoring tacks in the last and connecting said tacks by a binding wire which extends around the toe of the last and compressively retains the toe tip and box plank in position.

This method is open to the objection that when the shoe is passed to the welter, these anchoring tacks are frequently unobserved and are not withdrawn, with the result that in welting the needles frequently strike them and are broken. Moreover, the operation of driving the anchoring tacks and fixing the binding wire in position and of subsequently removing them represent additional operations which add to the manufacturing cost of the shoe, as does the expense of the anchoring tacks and wire.

I avoid these objections by dispensing entirely with the use of the anchoring tacks and binding wire so that the lasted toe may be passed from the pulling over machine to the welter without requiring the intervening operation of withdrawing the temporary anchoring tacks and removing the binding wire.

Broadly, my invention utilizes the inherent adhesiveness of the ordinary thermo-plastic box toe blank, when softened, as a binder to hold the box toe blank, insole and toe tip together, and consists in mechanically hardening, as by chilling, the softened box toe blank after it has been pulled over the toe tip and wiped in whereby to firmly set the adhering parts, so that the shoe may be passed at this stage directly to the welter. This chilling or hardening operation may be conveniently performed while the shoe is still in the bed lasting machine, so that the operator may be lasting the heel while the toe is hardening. Preferably the parts are caused to set by admitting a blast of cold air from an air nozzle directly upon them from the inside of the formed toe.

In the more specific adaptation of my invention which I shall discuss herein as illustrative of the principles involved and as showing a method which commends itself to accepted standards of manufacture, the outer face of the insole rib is first coated

with a thermo-plastic material, which is normally hard, but is adapted to be softened by heat, whereupon the insole so coated is tacked to the last and the last placed in the usual box toe heater, where the box toe blank is softened so that it may be pulled over the toe and sides of the last in the pulling over machine and the blank, toe tip and lining temporarily tacked to the last to hold them in place. The heat from the box toe heater is applied against the box toe blank at a point remote from the insole, so that the thermo-plastic coating on the insole rib is not affected by this heat application. After the box toe blank and toe tip has come from the pulling over machine, the shoe is next placed in a steamer which softens the entire toe, including the thermo-plastic coating on the insole rib so that this coating will adhere to the lining, as will the now softened box toe blank, when the shoe is placed in the bed lasting machine and the toe wiped in. The toe wipers may be set in this position while an air blast is directed over the toe from the inside so as to chill and harden the adhesive and cause the parts to be firmly united to each other. During this hardening step, the operation of pulling over the upper at the heel and tacking it may be performed.

This particular method of operation is specifically illustrated in the accompanying drawings, but it is to be understood that such showing is purely for the purposes of this application and in no way limiting. In the drawings:

Fig. 1 is a plan view of an insole having the rib or lip thereof coated around the entire toe with a thermo-plastic material which is normally hard but may be softened by heat.

Fig. 2 shows said insole tacked to a last upon which the upper, linings and box toe blank have been assembled for treatment at the box toe heater.

Fig. 3 shows the lasted box toe after it has been removed from the box toe heater of Fig. 2 and passed to the pulling over machine.

Fig. 4 shows the lasted box toe removed from the pulling over machine of Fig. 3 and placed in a steamer to soften the thermo-plastic material of both the box toe blank and the insole rib so that they will adhere to the toe tip when the box toe blank and tip are wiped in.

Fig. 5 shows the lasted box toe removed from the steamer of Fig. 4 and placed in the bed lasting machine and the toe wiped in to cause the toe blank, linings and insole to adhere to each other, and

Fig. 6 is a section on the line 6—6 of Fig. 5, showing one method of hardening the thermo-plastic coating of the box toe blank and insole rib to cause the parts to adhere to each other when set.

I have indicated at 1 an insole of conventional type provided with the usual marginal rib or lip 2 which is initially coated along its outer face with a thermo-plastic material 3 (Fig. 1) which is normally hard, but is adapted to be softened by heat. This coating 3 extends around the entire toe area of the insole coextensive with the area included by the box toe blank 4 shown in Fig. 2.

The insole 1, after being prepared as shown in Fig. 1, is tacked to the last L as indicated in Fig. 2, and the toe tip 5, box toe blank 4 and the usual linings 6 are assembled upon the last. The last is next placed in a box toe heater 7 of usual construction, in which the thermo-plastic material of the box toe blank, which at this stage is simply a flat, stiff piece of material, is softened, so that the box toe blank may be pulled over the toe and sides of the last when the last is placed in the pulling over machine, shown in Fig. 3. The heat from the box toe heater is applied to the box toe blank at a point remote from the insole so that this heat application has no effect upon the thermo-plastic coating 3 of the insole rib.

After the box toe blank has been sufficiently softened by the heating step shown in Fig. 2, the lasted box toe is removed to the pulling over machine (Fig. 3) and the box toe blank and upper and linings are pulled over the toe and sides of the last by the gripper jaws 8, and temporarily tacked to the last at three points, as indicated at 9.

The next step in my method consists in removing the lasted box toe from the pulling over machine and placing it in a steamer 10, Fig. 4, which softens both the box toe blank and the thermo-plastic coating 3 of the insole rib, so that the linings 6 will adhere, respectively, to the box toe blank, toe tip and the insole rib, whereupon the lasted box toe is removed from the steamer and placed in a bed lasting machine, Fig. 5, and the toe wiped in by the toe wipers 11 so as to press the box toe blank, linings, and insole to each other.

The toe wipers may be set in this position while the softened coating of the box toe blank and insole rib are hardened in any

suitable manner, as by chilling. In the hardening step, a blast of air from a valved delivery nozzle 12 (Fig. 6) is directed over the formed toe preferably interiorly thereof, the nozzle 12 being shaped to conform to the inside contour of the formed toe, and being supplied with air under pressure from any suitable supply source. While the toe is being set the operative may be pulling over the upper at the heel thereof and tacking it as indicated in Fig. 5.

My method thus not only avoids the use of the usual temporary anchoring tacks and binding wire and effects a considerable saving in both time and labor, but provides a box toe in which the toe blank, toe tip and insole are permanently united to each other throughout their mutually contacting surfaces.

Various modifications in the method of and apparatus for practicing my invention may obviously be resorted to within the limits of the appended claims.

What I therefore claim and desire to secure by Letters Patent is:

1. The method of forming a box toe which consists in coating a portion of the toe area of the insole with a normally stiff thermo-plastic material, in temporarily positioning said insole on a last to which is lasted a box toe blank of normally stiff thermo-plastic material and a toe tip, in applying to the box toe blank heat in a degree sufficient to soften said blank but insufficient to injure the toe tip or soften the thermo-plastic coating of the insole, in pulling over the softened box toe blank and the toe tip and temporarily tacking them to the last, in subjecting the lasted box toe to a heat application sufficient to again soften the box toe blank and to also soften the thermo-plastic coating of the insole, in wiping in the formed toe while so softened whereby to cause the box toe blank, toe tip and insole to adhere to each other, and in subsequently hardening the softened thermo-plastic coating of the box toe blank and insole to cause the box toe blank, toe tip and insole to intimately unite with each other.

2. A shoe comprising an insole having a rib coated in the toe area thereof with a normally stiff thermo-plastic material, and a box toe blank of normally stiff thermo-plastic material pulled over and wiped against the toe tip and insole when both the box toe blank and the insole rib are in a softened condition, and subsequently cooled to cause it to intimately unite with the toe tip and softened coating of the insole rib.

In testimony whereof I affix my signature.
JOHN J. DALY.
